United States Patent

Des. 234,915
Patented Apr. 15, 1975

234,915

CONTAINER FOR COSMETICS OR THE LIKE

Joseph J. Freedman, Scarsdale, N.Y., and Suzanne B. Grayson, Englewood, N.J., assignors to Lanvin-Charles of The Ritz, Inc., New York, N.Y.

Filed Nov. 22, 1971, Ser. No. 101,269

Term of patent 14 years

Int. Cl. D9—01

U.S. Cl. D9—164

FIG. 1

FIG. 2

FIG. 3

FIG. 4

FIG. 5

FIG. 1 is a front perspective view of a container for cosmetics or the like showing my new design;

FIG. 2 is a rear elevational view;

FIG. 3 is a side elevational view;

FIG. 4 is a top plan view; and

FIG. 5 is a bottom plan view thereof.

We claim:

The ornamental design for a container for cosmetics or the like, substantially as shown.
